LOOSE LEAF BINDER

Jay Raymond Newland, Kalamazoo, and Eugene T. Lundeen, Mattawan, Mich., assignors to Remington Rand Inc., Buffalo, N. Y.

Application May 19, 1932. Serial No. 612,326

1 Claim. (Cl. 129—13)

This invention relates to loose leaf binders and provides a simplified form of binder having only one binder post. This binder is particularly adapted to be used in systems where a series of cards or sheets are used, the individual cards or sheets containing information about different accounts or conditions. It is often desirable to separate cards in these systems into separate groups for tabulating reference or other purposes and it has heretofore been necessary to detach the cards from the binder to accomplish this result. It is possible by this invention to segregate or group together any of the cards of the series without removing them from the binder and also to lock the binder with the cards in any desired grouped position to prevent their accidental displacement.

The structure for obtaining the foregoing results comprises two binder members joined by only one binding member or post, a series of cards or sheets and means for locking the binder members together either in a position in which the cards are loosely held and free to rotate about the binding member, or in a position in which the cards are tightly clamped together. Positioning means are also provided on one of the binder members to hold a desired number of cards in a desired position on one of said binder members whether the cards are clamped thereon or not.

Other objects of this invention will appear in the specification and claim below.

In the drawings:

Fig. 1 shows the loose leaf binder in perspective with a stack of sheets arranged in several different positions relative to each other.

Fig. 2 is a longitudinal section through the binder shown in Fig. 1, with a slight rearrangement of the sheets.

Fig. 3 shows the positioning prong structure in perspective, detached from the binder.

Fig. 4 is an enlarged cross section taken through the center of the prong structure shown in Fig. 3.

Fig. 5 is a group perspective showing the base and cover of the binder in disassembled relation.

Fig. 6 is an enlarged transverse section taken on line 6—6 of Fig. 2, of the binder post with the locking mechanism in its locked position and with the leaves shown in broken lines.

The binder has a base member 1 made of wood, metal or any other suitable material that may be rectangular, square, round or any other desired shape.

A post 2 is fixed in base member 1. The post 2 may be secured in any suitable manner to the

base member 1 and in this instance said post projects through a circular orifice in the base member and has an annular flange 3 extending beyond the body of the orifice countersunk into the underneath portion of the base member and secured by rivets 4.

A removable binder member 5 of metal or other substantially rigid material acts as a clamping bar for the binder and is provided with a cover section 6 hinged to member 5 at 7. Cover section 6 is constructed of leather or any other suitable flexible material, although any rigid material may be used. A cover member 19 is provided on the opposite side of the binder or clamping member 5 from the cover 6, and is secured in any desirable manner to binder member 5, in this particular instance by rivets 8. The cover section 19 is also formed of a suitable flexible material, such as leather.

The clamping bar 5 is provided with a centrally disposed orifice in which is rigidly secured a downwardly depending tube 9. The tube 9 is secured in the orifice by means of an outwardly extending flange, as shown in Fig. 6, and cooperates with and slidably fits into the binder post 2 and is provided with a locking mechanism for locking the cover and base together. The free end of tube 9 is split into four quarters, shown at 10, in order that the tube at its free end may be expanded to engage post 2. The inner wall 85 of the free end of the tube is tapered inwardly as shown at 11, while the inside of the neck of tube 9 is threaded at 12 and receives the corresponding threads on pin 13. The pin 13 extends down into the narrowed portion 11 of the tube 90 and is rounded on its lower end, its upper end being provided with an enlarged head portion 14, the lower shoulder of which limits the downward movement of the pin by contacting with the top of tube 9. The head 14 is provided with an enlarged ring handle 15, secured in the usual manner through a hole 16 and provides a handle of sufficient size to facilitate the easy operation of the entire locking mechanism.

The operation of the locking mechanism is as follows: The tube 9 is partially slid into the binder post 2 and the pin 13, the lower end of which is not engaged with the tube at 11, is rotated by means of handle 15, the action of the screw threads causing the pin to advance into engagement with the inner surface of the tube 9, approximately at 11, and continued rotation of the pin causes expansion of the quartered ends of the tube and finally causes them to lock tightly with binder post 2, at 17.

The locking action just described is the same no matter what position the cover 6 may have relative to base 1, or no matter how far tube 9 may be inserted into the binder post.

5 A stack of sheets or cards 18 of any suitable size is provided in the binder, and in the preferred form as shown in Figs. 1 and 2, the cards are slightly smaller in dimension than the length and width of the top covers and are provided 10 with an aperture slightly larger than the binder bar 2 and positioned between the cover and the base member. To insert the sheets the cover member is disengaged from the base and the binder post inserted through the aperture of each 15 sheet. Usually the sheets are too numerous to be accommodated by the binder post alone so the remainder are positioned with their apertures in alignment coaxially above the binder post. The tube member 9 is then inserted through the card 20 apertures and into the binder post and serves as a retainer for the sheets located above the top of the binder post.

25 After the entire binder has been assembled and the binder locked without forcing the clamping bar down on the sheets, it is possible for any number of the sheets to be rotated laterally around the binder post 2 and tube 9, and to lock them in any desired position by loosening the locking mechanism, pressing downwardly on the 30 clamping bar, and then tightening the locking mechanism, for example, as shown in Figs. 1 and 2.

35 The adaptability of this binder in providing a multiplicity of possible positions for any number of its cards and the ability to lock the cards in any desired position is easily apparent and of substantial value and importance. With this binder it is possible in a business where the stub payment system is used to segregate, in the same 40 binder, the sheets pertaining to different individuals, or firms, as to which the same condition or status might exist and to group them in a vertical position one above the other, without removing them from the binder, at any desired 45 point around the axis of the binder post. It is also possible to lock the sheets in any desired predetermined method of segregation so that they will not be accidentally disturbed or disarranged.

50 It will be understood that the base member 1 and clamping bar 5 form a pair of binder members connected by a binding means or member formed by the post 9 engaging binder post 2 and its associated locking mechanism so that the 55 sheet body is rotatable about the single connection between the binders either as a unit or through the rotation of individual sheets for the purposes hereinabove set forth.

60 A positioning prong structure 20 is mounted in a transverse recess provided in the base mem-

ber 1 and is in the form of a U-shaped rod, having the two legs 21 and 21' lying immediately adjacent and parallel to the opposite sides of the base member 1, when the prong structure is in a horizontal or inoperative position. The 80 prong structure is preferably formed from a round rod and the portion of the structure connecting its two legs is provided in the central portion with two flat sides at right angles to each other at 22 and 23, as shown in Fig. 3. The 85 two sides 22 and 23 are cut into the round rod leaving edges 24. A horizontal recess 25 is also cut in the base member 1, this recess intersecting at right angles the transverse recess in the base member. A strip of spring metal 26 is 90 mounted in the longitudinal recess 25 and secured near one end by a rivet 27. The spring 26 overlies the flat sides 22 and 23 of the prong structure and is secured near its opposite end by a screw threaded bolt 28, the bolt 28 extending through base member 1 and engaging in nut 29, countersunk in the underneath face of the base member. Bolt 28 may be tightened or loosened to increase or decrease the tension of the strip on the prong structure 20. The strip 95 26 is of sufficient width so that its sides abut the edges 24 of the prong structure, whereby the prong structure is held against transverse movement.

The prong structure 20 may be rotated from 100 the position shown in Fig. 5 until its ends are in a vertical position, and the retaining strip by bearing upon the flat surface 22, will retain it in such position. The retaining strip will likewise retain the prong structure in its horizontal 110 position by bearing on the flat surface 23, after the prong structure has been moved to its horizontal position.

The prong structure, when in its vertical position, may be used to retain in position and in 115 vertical alignment, any of the stack of sheets or cards positioned between its two ends, even if the binder is not locked. If it is found desirable a similar prong structure may be provided for the opposite end of the base member 1. 120

The invention claimed is:

A loose leaf binder comprising a base member having a hollow binder post, a clamping bar provided with a downwardly depending hollow tube, said tube fitting into said binder post, locking 125 means in said tube for detachably locking said tube in the binder post, a series of sheets secured to and rotatable about said tube and binder post and positioning prongs on said base member for retaining said series of sheets in one position on 130 said base member when the locking means are inoperative.
